FIG1

FIG2

FIG4

FIG3

FIG5

FIGURE 1 is a perspective view, taken from the left front of a ski-bob embodying our new design;

FIGURE 2 is a perspective view, taken from the right rear, of the ski-bob of FIGURE 1;

FIGURE 3 is a left-side-elevational view of the ski-bob of FIGURE 1, the right-side-elevational view being symmetrically identical;

FIGURE 4 is a top plan view of the ski-bob of FIGURE 1; and

FIGURE 5 is a right side elevational view of the ski-bob of FIGURE 1 in the transportation position of the parts, the left side elevational view being symmetrically identical.

We claim:

The ornamental design for a ski-bob, as shown.
